Primary Examiner — Rhea Shields*(74) Attorney, Agent, or Firm* — Barnes & Thornburg LLP(57) **CLAIM**

The ornamental design for a filter housing with tube ports, as shown and described.

DESCRIPTION

FIG. 1 is a front perspective view of a filter housing with tube ports in accordance with our design, as viewed from a top right corner thereof;

FIG. 2 is another front perspective view thereof, as viewed from a bottom right corner thereof;

FIG. 3 is a further front perspective view thereof, as viewed from a top left corner thereof;

FIG. 4 is a rear perspective view thereof;

FIG. 5 is a front elevation view thereof;

FIG. 6 is a top plan view thereof;

FIG. 7 is a bottom plan view thereof;

FIG. 8 is a side elevation view of the right side thereof;

FIG. 9 is a side elevation view of the left side thereof; and,

FIG. 10 is a rear elevation view thereof.

In the drawings, the broken lines are for the purpose of illustrating environment only and form no part of the claimed design.
